ATTORNEY

UNITED STATES PATENT OFFICE.

HARRY A. ROSS, OF BLYTHEVILLE, ARKANSAS.

WASHBOARD.

1,279,761.

Specification of Letters Patent. Patented Sept. 24, 1918.

Application filed June 16, 1916. Serial No. 104,052.

To all whom it may concern:

Be it known that I, HARRY A. Ross, a citizen of the United States, residing at Blytheville, in the county of Mississippi and State of Arkansas, have invented certain new and useful Improvements in Washboards, of which the following is a specification.

My invention relates to wash boards and the primary object thereof contemplates the provision of the device of this character wherein is provided a brush means adapted to efficiently clean clothes causing only a minimum amount of wear on the clothes while the latter are being engaged therewith, and, also to operatively associate with this brush means, a plurality of oscillating rollers arranged to facilitate the rubbing of the clothes over the brush means.

Another object of this invention resides in the provision of novel means for association with the ends of the rollers and with the side pieces to prevent the rollers and side pieces from swelling after continuous use in warm water consequently increasing the efficiency of the operation of the rollers.

It is a more specific object of this invention to provide a plurality of large rollers and arrange one of them to bear against the top row of brush bristles so as to force the latter downwardly against the adjacent row of bristles to consequently prevent these bristles from throwing water rearwardly or upwardly on the operator; and to arrange tufts of bristles alternately with openings in the brush body to allow suds and dirty water to pass through the openings and fall into the tub without being caused to flow down the length of the body.

A still further object of my invention resides in the provision of a device of the character described that is simple in construction, efficient in operation and one that can be manufactured and placed on the market at a minimum cost.

Other objects as well as the nature, characteristic features and scope of my invention will be more readily understood from the following description taken in connection with the accompanying drawings and pointed out in the claims forming a part of this specification.

In the drawings:

Figure 1 is a front elevation;

Fig. 2 is a vertical section taken on the line 2—2 of Fig. 1;

Fig. 3 is a transverse section taken on line 3—3 of Fig. 1;

Fig. 4 is an enlarged detail.

Referring more particularly to the drawings, I provide a frame comprising preferably side pieces 1 and 2, to the upper ends of which is connected the head piece 3. A cross piece 4 is rigidly secured between the side pieces and arranged in spaced relation to the head piece. Receivable between and connected to the head piece 3 and the cross piece 4 and also connected to the side pieces 1 and 2 is a board 5 which provides a bottom for the soap box.

In order to efficiently clean clothes without exercising a great amount of wear thereon during the cleaning and rubbing operation I have provided my improved brush means. In the present instance this means comprises a rectangular body 6 which is arranged transversely on the side pieces 1 and 2 and connected in recesses 7 in the rear faces of the side pieces approximately intermediate the lower ends of the pieces and the cross piece 4, preferably through the medium of screws 8. The body is provided with a plurality of alternately arranged openings 9. These openings are arranged also in parallel rows while in the alternate openings in each row are arranged tufts of bristles 10 which are placed alternately to the bristles in the adjacent row, the arrangement being clearly illustrated to advantage in the drawings. Likewise it will be noted that an opening is arranged adjacent each tuft of bristles to permit soap suds and dirty water to pass therethrough without being caused to flow down the full length of the body before entering the tub, not shown.

In order to facilitate the rubbing of clothes over the brush means I have provided a plurality of large rollers 11 and a plurality of smaller rollers 12. The inner faces of each of side pieces 1 and 2 are provided with a plurality of recesses disposed in spaced groups. The recesses in each group are adapted to receive the continuous metal sockets 13, shown in Fig. 4. Metallic caps 14 are carried upon the respective ends of the rollers and are adapted to be journaled in the sockets 13. These sockets and caps prevent the rollers and side pieces from swelling after the wash board has been continu-

ously used in warm water. Incidentally the large rollers 11 are positioned in a plane in advance of the plane of the outer edges of the bristles 10 and the lower of the large rollers 14 is arranged to bear against the upper row of tufts of bristles 10 to consequently force the latter downwardly against the adjacent row. By this arrangement the liability of the bristles splattering water and suds upon the operator is lessened. After the board has been used the bristles will tend to assume a downwardly inclined position as illustrated in Fig. 2. The bristles will then serve to prevent splashing of the water upwardly. It will be appreciated that these rollers are not designed for cleaning purposes but on the other hand rotate or oscillate to facilitate the pushing and pulling of clothes back and forth over the brush. It is to be appreciated that when the bristles in the brush body have become worn the body can be readily removed and the new one associated with the recess. If the bristles are arranged in advance of the rollers strips of card-board or the like may be readily interposed between the bottom of the recess 7 on the body 6 so that a proper adjustment may be attained for the bristles.

From the above description taken in connection with the accompanying drawing, it can easily be seen that I have provided a device that is simple in construction, containing but a few simple parts that can be cheaply manufactured and assembled and when assembled can be placed upon the market and sold at a minimum cost.

It will be understood that the above description and accompanying drawings comprehend only the general embodiment of my

invention and that various minor changes 40 in detail of construction, proportion and arrangement of the parts may be made within the scope of the appended claims and without sacrificing any of the advantages of my invention. 45

Having thus fully described my invention what I claim as new and desire to secure by Letters Patent, is:

1. A wash board, which comprises a frame, a brush body removably secured to the frame, tufts of bristles arranged in spaced vertical and longitudinal rows on the body, a plurality of different diametered rollers rotatably mounted in the frame and arranged in groups transversely adjacent the upper and lower ends of the body, the lower one of the upper rollers being adapted to bear against the upper row of bristles to prevent splattering of water on the operator while rubbing clothes over the bristles. 60

2. A wash board, which comprises a frame, a brush body removably connected with the frame and provided with a plurality of spaced openings therein, a plurality of spaced tufts of bristles projecting 65 from the brush body, each tuft of bristles being disposed near one of said openings, and a plurality of spaced rollers rotatably mounted and arranged in groups adjacent each of the upper and lower ends of said brush body.

In testimony whereof I affix my signature in presence of two witnesses.

HARRY A. ROSS.
